UNITED STATES PATENT OFFICE

122,380

DESIGN FOR A BARRETTE

Siegfried Behr, Flushing, N. Y.

Application March 20, 1940, Serial No. 91,098

Term of patent 7 years

To all whom it may concern:

Be it known that I, Siegfried Behr, a citizen of the United States, residing at Flushing, county of Queens, State of New York, have invented a new, original and ornamental Design for a Barrette, of which the following is a specification, reference being had to the accompanying drawing, forming part thereof.

Fig. 1 is a front view of a barrette showing my new design.

Fig. 2 is a top plan view of the same.

I claim:

The ornamental design for a barrette, as shown.

SIEGFRIED BEHR.
